UNITED STATES PATENT OFFICE.

SINAI LETIECQ, OF WORCESTER, MASSACHUSETTS.

DEVICE FOR JOINING ELECTRICAL CONDUCTORS.

1,315,317.

Specification of Letters Patent.

Patented Sept. 9, 1919.

Application filed July 3, 1918. Serial No. 243,136.

To all whom it may concern:

Be it known that I, SINAI LETIECQ, a citizen of the United States, residing at Worcester, in the county of Worcester and Commonwealth of Massachusetts, have invented a new and useful Improvement in Devices for Joining Electrical Conductors, of which the following, together with the accompanying drawings, is a specification.

10 The object of my present invention is to provide a readily applied device to an electrical conductor, preferably of the flexible variety, by which an electrical connection may be made between said conductor and a supplemental or auxiliary conductor. Another object of my invention is to enable the lines of conductors to be multiplied from a single line, and further to effect the junction of the supplemental lines at any point 20 of a connected line which may be desired, and these objects among others I accomplish by the device hereinafter described, the features of novelty being pointed out in the appended claims.

25 Referring to the drawings, Figure 1 is a perspective view of a device embodying my present invention, but having the compression cap, shown in Fig. 6, removed.

Fig. 2 is an elevation of my improved 30 device showing the rear side.

Fig. 3 is an elevation showing the front side, but having the compression cap removed.

Fig. 4 is a sectional view through the center of the stem 2.

Fig. 5 is a rear view of the contact chamber with the binding screws removed.

Fig. 6 is a perspective view of the compression cap detached from the device.

40 Fig. 7 is a central sectional view through the head of the device, the section being taken on the plane of the broken line 7—7, Fig. 1.

Fig. 8 is a front sectional view on the 45 plane between the head 1 and the screw threaded boss 3, showing the arrangement of the pins 21.

Similar reference characters refer to similar parts in the different figures.

50 The device embodying my present invention comprises a cylindrical head 1. Projecting from the head 1 is a stem 2, and projecting from one side of the head but in axial alignment therewith is a screwthreaded 55 boss 3 having a central slit or opening 4,

said screwthreaded boss 3 being adapted to receive the cylindrical screwthreaded cap 5, shown detached in Fig. 6. The parts 1 to 5 inclusive are made of nonconducting material. The stem 2 is hollow and communicates with a contact chamber 6 in the head 1, Figs. 4 and 5. The interior wall of the contact chamber 6 is screwthreaded, as shown at 7, Fig. 7, and is closed by a plug 8 having a slit 9 for a screw-driver. The hollow stem 2 contains the supplemental 60 conducting line 10, consisting in the present instance of the two insulated wires 11 and 12, the free ends of which are clamped between washers 13 and 14. The washers 13 and 14 are held upon binding screws 15 and 16. Lying against the bottom of the contact chamber 6 and clamped beneath the washers 14 are wires 17 and 18, said wires terminating in pins 19 and 20 which pass 70 through the nonconducting material of which the head is composed and project a short distance into the slot 4, as shown at 21, Fig. 7. The projections 21 are arranged in pairs upon each side of the slot 4, as 75 shown in Fig. 8. The pins of one pair have a staggered relation to the pins of the other pair, as shown in Fig. 8, and are adapted to pierce the insulation of the main conducting line, consisting of the two insulated 80 wires 23, and 24, Fig. 1, forming a twisted cable 22. The object of arranging the pins in staggered relation, as above described, is to enable the pins of each pair to pierce the insulation material of the cable 22 on opposite sides of the conducting wires 23 and 24. The slots 4 of the screwthreaded boss 3 are placed on diametrically opposite sides of the boss and are just wide enough to admit the twisted wires of the main cable 22 90 at their narrowest points 25, as represented in Fig. 3, thereby determining the position of the twisted cable as it is forced upon the pins 21.

When the main cable 22 has been placed 100 in position in the screwthreaded boss 3, as shown by the dotted lines in Fig. 3, the cap 5 is screwed upon the boss with the compression plug 26 entering the slot 4. As the cap 5 is screwed upon the boss 3 the plug 26 105 will crowd the main cable 22 upon the pins 21 causing the pins 21 to pierce the insulation of the cable and be brought in contact with the conducting wires 23 and 24. As the compression plug 26 is held from turn- 110

ing in the slot 4 while the cap 5 is being screwed upon the boss 3 a swivel joint is provided between the compression plug and the head of the cap, by means of an attaching screw 27 which is held in the plug 26 and free to turn in the head of the cap 5. The main cable 22 is connected with the source of an electrical supply and constitutes the main conducting line with which

10 the supplemental line 10 is electrically connected by means of the device forming the subject of my present invention, in the manner above described. In case the main line 22 becomes severed with a short piece connected with the source of supply, the supplemental line 10 can be attached to the piece remaining, or, a series of supplemental lines 10 can be connected at different points with the main line 22.

20 My device may be employed in shops where an incandescent lamp is suspended over a machine, for the purpose of taking off a branch line carrying a portable lamp, for the purpose of inspecting a machine 25 being set up, or for furnishing light at an adjoining bench. In such cases, a lamp can be suspended from the cable 22, and a portable lamp attached to the line 10, which may be readily connected at any point to the 30 main cable 22.

My device will also be found useful on shipboard, or in military trenches, where the main line is liable to become severed, by allowing the supplemental line to be attached beyond the point of separation. My device is particularly adapted to forming a junction with any flexible line consisting of a twisted cable, as the position of the cable upon the pins 21 is predetermined by the 40 width of the slots 4 which can only admit the cable at its narrowest points 25, 25, as represented in Fig. 3, and as the staggered pins 21 are so disposed that they would pierce the insulation on opposite sides of the 45 conducting wire, as already described. As the space between the slots 4, 4 is wider than the slots, the two members of a twisted cable such as that shown at 22, Fig. 1, and by broken lines in Fig. 3, will be pressed down 50 against the pointed spurs 21 by the plug 26.

I claim,

1. The combination with a head of insulating material having a screwthreaded boss on one side, provided with a diametrical slot 55 to receive a flexible cable forming part of an electrical circuit, of a supplemental cable held by said head and having pointed terminals projecting into said slot, a screwthreaded cap engaging said boss, and a swiv-

eled plug carried by said cap and entering 60 said slot.

2. The combination of a cylindrical head of insulating material provided with a transverse slot, a supplemental electrical cable carried by said head provided with 65 pointed terminals entering said slot, a flexible cable forming part of an electrical circuit and held in said slot, a plug inclosed in said slot and bearing against said flexible cable, and means for forcing the plug 70 against the flexible cable.

3. The combination of a head, pointed terminals carried by said head and insulated therefrom, a screwthreaded boss projecting from said head and having a slot to receive 75 a twisted cable, a screwthreaded cap carried by said head, and a swiveled plug carried by said cap and entering said slot, and a supplemental cable carried by said head and electrically connected with said terminals.

4. The combination of a head provided with a slot to receive a cable, a second cable held by said head, pointed terminals held by said head and electrically connected 85 with said second cable, a cap having a screw threaded connection with said head, and a plug carried by said cap and inclosed in said slot, said cap being capable of rotating independently of said plug.

5. The combination of a head provided with a slot to receive a cable, a second cable held by said head, pointed terminals held by said head and electrically connected with said second cable, a cap having a screw 95 threaded connection with said head, and a plug carried by said cap and rotatable independently of the cap, said plug projecting beyond said cap.

6. The combination with a head of insulating material having a screw threaded boss on one side, provided with a diametrical slot to receive a cable comprising two individual strands, with the central portion of said slot wider than its ends and having the ends of 105 said slot slightly wider than the diameter of the individual strands of which the cable is composed, of a supplemental cable having pointed terminals entering the wider portion of said slot and on opposite sides of its 110 center, a screw threaded cap engaging said boss and a plug held in said slot gearing against said cap.

SINAÏ LETIECQ.
